UNITED STATES PATENT OFFICE

WALTER W. PETTIBONE, OF BIRMINGHAM, ALABAMA

PULVERIZER

Application filed July 19, 1929. Serial No. 379,462.

My invention relates to pulverizers and like means for reducing coal, minerals and other materials, and its object is to provide baffle means to prevent centrifugal ejection 5 of material through the supplemental air inlets provided adjacent to the fan chamber from which the finished material is blown to discharge it from the pulverizer.

In pulverizers, the material under treatment after passing through the required number of reduction stages is delivered to a discharge chamber from which it is blown by a fan to the point of use and it has been found necessary to interpose a supplemental air inlet chamber adjacent to the fan chamber to permit of the fan functioning properly in the discharge of the pulverized material.

In practice it has been found that there is a tendency of the whirling mass of material responsive to centrifugal force, to separate more or less of the larger particles from the reduced mass flowing to the fan chamber and to eject such particles through the supplemental air inlet ports, and the particular object of this invention is to prevent this and to return such separated particles to the machine for further reduction.

My invention contemplates the provision, in a peripheral wall of the supplemental air inlet chamber, of air inlet openings which are guarded by inwardly inclined deflector lips or flanges adapted to deflect whirling particles of material so that they will jump the air inlet openings and thus I avoid the wasting of material through the air openings without interfering with the free inflow of air.

A further object is to take advantage of the fact that the coarser unreduced particles of material alone will reach the outer peripheral wall of the supplemental air inlet chamber, and by adapting the baffles to deflect these larger whirling particles inwardly they will tend to become separated from the finer material passing to the fan chamber and because of the proper relation of the inlet and outlet openings for said supplemental air chamber, these coarser particles will be returned to the last treatment chamber and there acted upon to complete their reduction.

My invention further comprises the novel details of construction and arrangements of parts which are hereinafter more particularly described and claimed and which, in their preferred embodiment only, are illustrated in the accompanying drawings, forming a part of this application and in which:

Fig. 1 is a longitudinal vertical cross sectional view of a pulverizing machine.

Fig. 2 is a transverse cross sectional view of Fig. 1 taken on the line II—II.

Similar reference numerals refer to similar parts throughout the drawings.

I have chosen the conventional type of multi-stage coal pulverizer as a suitable embodiment for illustrating my present invention, the pulverizer comprising a casing 5, a feed mechanism 6, an annular partition 7 dividing the last working stage from the supplemental air inlet chamber 8 which in turn is subdivided by an annular partition 9 from the chamber 10 in which the fan 11 is mounted. This fan, driven by shaft 12, acts in a manner, well understood in this art, to draw in the reduced material along with the supplemental supply of air entering the air inlet chamber and deliver said material through a suitable discharge 13 to the point of use. All the parts thus far described are of standard construction and may be widely varied according to conditions of use.

I show the supplemental air inlet chamber 8 formed with an outer peripheral wall 14 which separates said chamber from an annular air supply chamber 15 having openings 16, preferably in its outer side wall at diametrically opposite points, to admit thereto the supplemental supply of air. The wall 14 of the air chamber has any desired number of air inlet ports 17 and each port on the side of the approach of the whirling material, has an inwardly inclined deflector lip or baffle 18, which extends a sufficient distance inwardly from the outer wall to cause any particles of the pulverized material, that gain access to the air chamber and are caused to whirl therein, to be sufficiently deflected inwardly to jump the air ports and be retained within the machine. These deflectors are preferably coextensive in width with the

air chamber 8 and in the construction shown are formed by inclining the outer marginal wall 14 inwardly on the approach side of each air inlet port to a point close to the inner edge of the annular partition 7.

It will be noted that the opening in the annular partition 7, through which material enters the supplemental air inlet chamber, is materially greater in diameter than the opening in partition 9 giving into the fan chamber. Preferably the baffles 18 extend close to the opening in partition 7 and as a result of this arrangement it will be seen that any particles arrested by the baffles will tend to pass back into the last treatment chamber and not to pass into the fan chamber with the reduced material. By taking advantage of this construction the deflectors will cause such larger unreduced particles as may escape from the flow of material to the fan chamber to be returned and where necessary be further reduced, thus preventing their accumulation within the machine or their escapes therefrom through the air inlet opening.

In operation, the great mass of reduced material passes directly across the supplemental air inlet chamber into the fan chamber and is discharged, but all of the material is traveling in a whirl about the axis of the pulverizer and this whirl causes the larger, heavier particles to collect about the periphery of the mass under treatment and thus they become separated from the reduced material and gain access to the outer periphery of the supplemental air inlet chamber. As they whirl in this chamber they engage the deflectors and are thrown back toward the center of the machine where, if fine enough, they will pass out to the fan chamber or if coarse they will pass back into the last treatment chamber and become subject to further reduction.

While I have shown the outer wall and deflectors of the air treatment chamber as formed by a casting integral with the fan housing, it is to be understood that the equivalent of this wall can be applied to an existing pulverizer in any suitable and economical way adapted to effect the deflection of the whirling material sufficiently to jump the supplemental air inlet ports.

While I have shown my invention in but one form it will be obvious to those skilled in the art that it is not so limited but is susceptible of various changes and modifications without departing from the spirit thereof and I desire therefore that only such limitations shall be placed thereupon as are imposed by the prior art, or as are specifically set forth in the appended claims.

What I claim is:

1. In a pulverizer, a casing divided by transverse annular partitions into chambers successively adapted for the reduction of material, the inlet of supplemental air, and the

discharge by a fan of the reduced material, the said air chamber having air inlet ports in its peripheral wall each grooved by an inwardly inclined baffle extending into juxtaposition to the inner edge of the partition on the inner side of the air chamber, the opening in the partition on the outer side of the air chamber being materially less in diameter than the opening on its inner side partition. 70

2. In a pulverizer embodying in series a reduction chamber, an air inlet chamber and a fan chamber, partition walls between the chambers having axially arranged openings therein for the passage of air and reduced materials, and a series of inwardly inclined baffles disposed within the air inlet chamber and effective to divert heavier particles of material through the opening into the preceding reduction chamber. 75

3. In a pulverizer embodying in series a reduction chamber, an air inlet chamber and a fan chamber, partition walls between the chambers having axially arranged openings therein for the passage of air and reduced materials, an outer peripheral wall for the air inlet chamber, said wall having a plurality of air inlet openings therein, and inwardly inclined deflectors provided on the outer peripheral wall adjacent said openings for diverting heavier materials through the axially arranged opening into the preceding reduction chamber for further treatment. 80

4. In a pulverizer embodying in series a reduction chamber, an air inlet chamber and a fan chamber, partition walls between the chambers having axially arranged openings therein for the passage of air and reduced materials, an outer peripheral wall for the air inlet chamber, said wall having a plurality of air inlet openings therein, and inwardly inclined deflectors provided on the outer peripheral wall adjacent said openings for diverting heavier materials through the axially arranged opening into the preceding reduction chamber for further treatment, the diameter of said air inlet chamber enclosed by the outer peripheral wall being substantially greater than the axially arranged opening into the fan chamber. 100

In testimony whereof I affix my signature. 105
